UNITED STATES PATENT OFFICE.

WILLIAM E. BUTLER AND MORGAN L. LANE, OF OMAHA, NEBRASKA.

POLE-CHANGER.

No. 890,840.

Specification of Letters Patent.

Patented June 16, 1908.

Application filed March 11, 1908. Serial No. 420,463.

To all whom it may concern:

Be it known that we, WILLIAM E. BUTLER and MORGAN L. LANE, citizens of the United States, residing at Omaha, in the county of

5 Douglas, State of Nebraska, have invented a new and useful Pole-Changer, of which the following is a specification.

This invention has reference to improvements in pole changers designed more particularly for use in telephone systems where it is desired to selectively operate two or more telephone signal bells upon the same line. This is done by impressing upon the line from a direct current source a succession 10 of positive pulsations, a succession of negative pulsations, and an alternating current, with means for causing any one of these three types of current to be impressed upon the line at any one time. The signal receiving 15 devices are, of course, properly constructed to respond to any predetermined one of the types of current and to no others, so that no matter what number of signal devices there may be upon the single line, within the 20 limits of the number of possible types of current, only the one signal device responsive to the particular type of current impressed will ring.

The present invention comprises a member 30 made up of three conducting blocks or plates arranged in longitudinal series and insulated one from the other with one of the end plateslapping but insulated from the intermediate plate and brought into close relation 35 but still insulated from the other end plate. In conjunction with these several plates are three brushes adapted to make contact with but two of the plates at any one time, but always including the central plate except for 40 the exceedingly brief period of time when the brushes rest upon the insulating material, the latter being made just wide enough to eliminate danger of short circuit as a brush passes from one block to another. The construction is such that the impulses, both 45 positive and negative, are uniform and succeed each other regularly, and are of the same duration and strength, thus producing an even lively ring of the bell affected.

50 The invention will be best understood by reference to the following detail description, taken in connection with the accompanying drawings, in which drawings,

55 Figure 1 is a diagram of the pole changing device in its normal position, or position of rest, at which point the negative impulse is

being sent to line. Fig. 2 is a diagram showing the other phase of operation of the device, that is, when a positive impulse is going to line.

60 Referring to the drawings, there is shown a commutator 1 made up of three conducting blocks 2, 3 and 4 separated by insulating material 5. The block 3 is of less width than either of the blocks 2 or 4, while the block 4 65 has an extension 6 lying alongside of the block 3 and approaching the block 2 as closely as does the block 3, but separated from the said block 3 by insulating material. On one side of the commutator 1 there are 70 two spaced brushes 7, 8, and on the other side of the commutator in line with the brush 7 is still another brush 9.

In the drawings, there is shown a simple, 75 but effective, means of imparting longitudinal movement in both directions to the commutator 1, but this means is not to be taken as the only means which may be used for the purpose, since any means which will impart to the commutator 1 a to and fro 80 longitudinal movement may be used.

In the specific form shown in the drawings, the commutator is mounted upon a rod 10 about midway of the length of the latter, and this rod has bearings 11 in a suitable 85 frame 12, in which bearings the rod is capable of sliding. If the rod is round, then it may be kept from turning by a suitable spline, or the rod may be otherwise shaped than round, and the bearings be made to 90 conform to that shape and thus keep the rod from turning. Between the bearings 11, the rod is surrounded by short springs 13 constituting elastic buffers for the commutator 95 at the limits of its travel in either direction. Beyond one of the bearings 11, the rod is surrounded by a spring 14 confined between the bearing and a head 15 formed on the rod. Beyond the other bearing 11, the rod carries an armature 16 in operative relation to 100 an electro-magnet 17 which may be of the ordinary horseshoe type. One side of the magnet 17 is connected by a conductor 18 to the block 4 of the commutator. The other side of the magnet 17 is connected by a conductor 19 to one side of a battery 20 through the switch 21, and the battery is connected by a conductor 22 to another conductor 23 leading to the brush 9. Now, when the switch 21 is closed, the circuit is completed 105 through the conductor 19 to the magnets 17, thence by conductor 18 to the block 4, then 110

by way of the brush 9 and conductor 23 to the conductor 22 and back to the battery. The magnet 17 is thereby energized and attracts the armature 16 and moves the commutator 1 against the action of the spring 14. The impulse thus given to the commutator moves it longitudinally until the brush 9 passes to the block 2, when the circuit to the battery 20 being broken, the magnet 17 becomes de-energized and the spring 14 then moves the commutator 1 back to its original position. This again causes the magnet 17 to be energized, and the commutator is again drawn so that the brush 9 is once more brought in contact with the block 2, again breaking the circuit of the battery 20. This is repeated so long as the switch 21 remains closed. On the opening of the switch 21, the commutator resumes its initial position with the blocks 3 and 4 in contact with the brushes 7, 8 and 9, as shown in Fig. 1.

The main ringing battery is shown at 24, but, of course, any other suitable source of constant current may be used, and the showing of the battery 24 is to be taken as a conventional illustration of any kind of current source. The positive side of the battery 24 is connected by a conductor 25 to the brush 7, and by another conductor 26 to a ringing key 27, the showing of which is conventional and is illustrative of any kind of circuit making and breaking device adapted for the purpose. This key, 27, is connected by a conductor 28 to the switch board to be ultimately connected up to the desired line in the usual manner, but, as the switch board and line connections form no part of the present invention, and since the signal receiving means may be of the usual selective type responsive to the different types of current, it is not deemed necessary to show any of these devices, or the circuit connections, in the drawings.

The negative side of battery 24 is connected by a conductor 29 to the brush 8, and by another conductor 30 to the negative key 31 which, in turn, is connected by a conductor 32 to the switch board. The conductor 23 connected to the brush 9 and also to the conductor 22 is continued to the alternating key 33, which latter is connected by a conductor 34 to the switch board. The block 3 is connected by a conductor 35 to ground, indicated at 36, or it may be grounded through the frame of the apparatus, or in any other manner.

Now let it be assumed that the apparatus is in the position shown in Fig. 1, and let it be assumed that the key 31 is depressed, current will then flow from the positive side of the battery 24 through the conductor 25, to the brush 7, and thence to the block 3 and to ground through the conductor 35, thence returning through the conductor 32 and key 31 to the conductor 30 and back to the negative

side of the battery 24. This is under the assumption that at the signal receiving mechanisms one side thereof is grounded. If under the same conditions of the commutator, the alternating key 33 was closed instead of the negative key 31, then the current would go to ground as before, and the negative current would return from the key 33 through the conductor 23 to the brush 9, thence by way of the block 4 to the brush 8 and through the conductor 29 to the negative side of the battery. Now, let it be assumed that the magnet 17 is energized and the commutator 1 is moved to the position shown in Fig. 2. Under these conditions, the positive side of the battery is connected up by the conductor 26 to the positive key 27, and, assuming that this key is closed, the positive current impulse would flow to the corresponding signal apparatus and be there grounded, returning through the conductor 35 to the block 3 and by way of brush 8 and conductor 29 to the negative side of the battery. Suppose that under the last-named conditions regarding the commutator that the key 33 is closed instead of the key 27, then the positive impulse will flow by way of conductor 25 to the brush 7 through the block 2 to the brush 9 and by way of the conductor 23 through the key 33 to the respective signal apparatus, returning as before through the conductor 35 and block 3, brush 8 and conductor 29 to the negative side of the battery. Thus it will be seen that in the position of the parts shown in Fig. 1, negative impulses may be established upon the lines 32 and 34, while in the position of the parts shown in Fig. 2, positive impulses may be established upon the lines 28 and 34. When the magnet 17 is alternately energized and de-magnetized by the action of the commutator 1 upon the circuit of the battery 20, then the conditions are such that if the negative key 31 is closed, there are thrown upon the line a succession of negative impulses separated by dead spaces of substantially the same time length as the impulses, and the succeeding impulses are of equal length and uniform current strength. When the positive key 27 is closed, then there are thrown upon the line positive impulses of even length and uniform current strength separated by like dead spaces. When the alternating key 33 is closed, then there is thrown upon the line a succession of alternately negative and positive impulses of equal length and current strength and succeeding each other with practically no dead spaces between them. Thus current conditions are produced that cause a crisp, clear, ringing of the call bells at the receiving stations. Furthermore, the circuit is always grounded after each impulse and therefore all condensers in the circuit are discharged.

The switch 21 is only indicative of the

means for breaking the circuit of the battery 20, and this may be arranged to close this battery circuit only when one of the current transmitting keys is closed, the mechanism 5 for vibrating the commutator remaining quiescent, except when a transmitting key is closed to energize the ringing circuit.

We claim:—

1. A means for transmitting to the ringing 10 circuits of telephone lines different types of current impulses from a constant current source, comprising circuits individually and positively coupled to the respective sides of the current source, and means for coupling 15 either the positive or negative side of the current source to the said other circuit and the respective other side of the current source to ground.
2. A pole changer for transmitting to the 20 ringing circuits of telephone lines different types of current impulses from a constant current source comprising three contact plates one of which is connected to ground, contact brushes connected to the opposite 25 poles of the constant current source, each brush being adapted to make contact with the ground plate and with a respective one of the other plates, circuit connections from each end of the current source to a respective 30 line circuit, and circuit making and breaking means in each of said connections.
3. A pole changer for transmitting to the 35 ringing circuits of telephone lines different types of current impulses from a constant current source comprising a commutator having three contact plates insulated one from the other with one of the end plates overlapping the intermediate plate and approaching the other end plate as closely as 40 does the intermediate plate, two spaced brushes arranged to engage each intermediate plate, and a respective one of the end plates when the commutator is moved longitudinally, a constant current source 45 connected at each end to a respective end of the current source, circuit connections leading from the current source, circuit making and breaking means for each of said connections, and means for moving the commutator 50 to and fro under the brushes.
4. A pole changer for transmitting to the 55 ringing surface of telephone lines different types of current impulses from a constant current source comprising a commutator having three contact plates insulated one from the other with one of the end plates overlapping the intermediate plate and approaching the other end plate as closely as does the intermediate plate, a brush adapted 60 to make contact with the intermediate plate and with a respective one of the end plates and connected to one side of the constant current source, another brush adapted

to make contact with the intermediate plate and the respective other one of the end 65 plates and connected to the other side of the constant current source, a third brush adapted to make contact with either of the end plates, and means for coupling up the brushes independently into respective 70 circuits.

5. A means for independently transmitting to the ringing circuits of telephone lines, positive, negative and alternating current 75 impulses from a single constant current source, comprising a commutator composed of three conducting blocks insulated one from the other with the end blocks in as close relation to each other as the intermediate block, a ground connection from the 80 intermediate block, means for imparting a to and fro longitudinal movement to the commutator, two spaced brushes arranged to make contact with the intermediate block and the respective one of the end 85 blocks under the different movements of the commutator, circuit connections between the said two brushes and the respective ends of a constant current source and also to line, circuit making and breaking devices in the 90 connections to line, another brush adapted to make contact with the end blocks in accordance with the position of the commutator, a circuit connection from the last-named brush to the line, and a circuit making and breaking device in the last-named 95 connection.

6. A means for transmitting to the ringing 100 circuits of telephone lines different types of current impulses from a source of constant current, comprising a circuit positively coupled to the positive side of the current source, another circuit positively coupled to the negative side of the current source, a third circuit, and means for coupling the 105 latter to the two poles of the current source in alternation.

7. A means for transmitting to the ringing 110 circuits of telephone lines different types of current impulses from a source of constant current, comprising a circuit positively coupled to the positive side of the current source, another circuit positively coupled to the negative side of the current source, a third circuit, means for coupling the latter to 115 the two poles of the current source in alternation, and means for completing any one or more of the circuits at will.

In testimony that we claim the foregoing as our own, we have hereto affixed our signatures in the presence of two witnesses.
